RICHARD H. RICE, OF LYNN, MASSACHUSETTS, ASSIGNOR TO GENERAL ELECTRIC COMPANY, A CORPORATION OF NEW YORK.

AUTOMATIC GOVERNING MECHANISM.

1,134,761.

Specification of Letters Patent. Patented Apr. 6, 1915.

Application filed February 10, 1914. Serial No. 817,810.

To all whom it may concern:

Be it known that I, RICHARD H. RICE, a citizen of the United States, residing at Lynn, county of Essex, State of Massachusetts, have invented certain new and useful Improvements in Automatic Governing Mechanism, of which the following is a specification.

The present invention relates to automatic governing mechanism and in particular to its application in a water gas producing system.

Briefly, a gas generating system including a water gas plant, as commonly arranged, comprises a generator containing a grate and a bed of red hot fuel connected by a suitable conduit to a carbureter and superheater. During the so-called blowing period air under pressure is supplied under the grate to cause combustion of the fuel and raise the temperature of the same. This supply of air is regulated so as to be sufficient to cause only partial oxidation of the carbon, the products from the combustion comprising quite an amount of carbon monoxid gas. The hot products of partial combustion then pass to the carbureter and superheater along with a further supply of air, termed secondary air, which supply is regulated to be just sufficient to complete the combustion of the carbon. This heats the fire brick of the carbureter and superheater. The products of combustion then pass off through the stack valve to the atmosphere. After the desired temperatures are reached for the bed of fuel and the carbureter and superheater, the supply of air is cut off by hand and the stack valve is closed. Steam is then passed through the fuel, and oil is supplied to the carbureter. This constitutes the gas making period and is continued until the parts are cooled to such an extent that it is not advantageous to continue. The steam is then cut off, the supply of air re-established, and the cycle repeated.

To obtain satisfactory operation it is of advantage that the supply of primary air be of substantially constant volume and as the bed of fuel offers a greater or lesser resistance to the passage of the air according to the thickness and condition of the same, it will be clear that the pressure at which the air must be furnished in order to provide constant volume must be suitably regulated.

The pressure of the secondary air is con-

siderably less than that of the primary air, and is supplied in gradually increasing amounts from the beginning to the end of the blowing period, this being accomplished by a hand operated throttling valve.

The proper manipulation of the various valves for governing the air compressor, supplies of air, etc. to the system obviously requires care and constant attention on the part of the station attendants if the best results are to be obtained.

An object of the present invention is to provide a system of the above referred to character wherein the supply of both primary and secondary air is automatically regulated so as to furnish the proper amounts and at the correct pressures.

A further object of my invention is to provide a novel form of variable volume governor.

Referring to the drawings wherein I have illustrated certain forms which my invention may take, Figure 1 is a diagrammatic view of a water gas plant embodying my improved automatic governing mechanism, and Fig. 2 is a modification.

The generator 1 contains a grate 2 supporting a bed of fuel 3. Primary air is supplied under the grate by a pipe 4 which has a stop valve 5. The products of partial combustion which include carbon monoxid, carbon dioxid and nitrogen compounds, are led off through a pipe 6 to the carbureter 6a. Between the generator and the carbureter a pipe 7 joins the pipe 6, for supplying the secondary air. A throttle valve 8 in said pipe is provided for cutting off the supply of secondary air.

The air is supplied to both pipes by any suitable blower, but I prefer to use a centrifugal air compressor 9 driven by a steam turbine 10. From the discharge outlet of the compressor air is delivered to the two branch pipes 4 and 7, preferably by the interposition of a header 11.

In the branch pipe 4, leading to the primary air inlet of the generator, is placed the primary constant volume governor. This consists of a disk 13 floating on the column of air and located in a section 14 of the air pipe which section is preferably enlarged and made of frusto-conical form. The velocity of the air produces a pressure on the float which is counterbalanced by a weight 15 on a graduated lever 16 pivoted to the

2

stem 17 of the float. With the weight set at the position marked for any given volume, the governor will be in equilibrium only when this volume is passing. A rod 18 is attached to the lever and operates a throttle valve 19 in a main 20 supplying steam to the turbine 10. When the governor moves the lever the throttle valve will open until the air compressor is supplying a sufficient volume of air to hold the float steady in a given position against the action of the weight 15. As soon as this condition is reached, equilibrium will be maintained and a constant volume of air will flow into the generator. A dash-pot 21 is connected to the lever 16 to dampen its oscillations.

The secondary air governor involves the use of a throttle valve which will automatically maintain such pressure beyond it as will force a desired volume through whatever restrictions may exist. The pressure preceding of course will be greater, but it may be of any value above that to be maintained beyond the governor. It has been stated that the pressure of the primary air is somewhat higher than that of the secondary air, so that the secondary governor serves to throttle the secondary air supply down to a given quantity. The governor comprises a disk 22 mounted on a stem 23 in a section 24 of the air pipe 7. This section is enlarged and is preferably of frusto-conical form as shown. The stem is connected to a butterfly valve 25 in the pipe beyond the section 24, which pipe is connected to the base of the frusto-conical section by the converging section 24^a. On the spindle of the valve and outside of the pipe is a beam 26 carrying a counterweight 27. As the quantity of air tends to increase so as to raise the float, the butterfly valve is partially closed so as to decrease the pressure in the pipe beyond, which will decrease the flow.

As already stated, in the operation of a water gas plant, it is necessary to increase gradually the volume of the secondary air, from the beginning to the end of the blowing process. In order to accomplish this automatically, the weight 27 is arranged to move so as to act at a constantly increasing radial distance from the spindle of the valve. To this end the weight 27 moves in an inclined guide 28 carried by the end of beam 26. This guide is made in the form of a dash pot filled with oil, the weight acting as the plunger. To regulate the motion of said weight a by-pass 29 connects the two ends of the dash-pot to permit the plunger to displace oil or other liquid in said dash-pot, and a regulating valve 30 controls the flow of said liquid through said by-pass. A handle 31 on the stem 31^a of the plunger enables it to be re-set when necessary, and a graduated scale 32 coöoperating with said

handle indicates the volume which is being delivered at any instant. I may also provide suitable manometers for indicating the pressure at desired points as shown for instance at 7^a and 7^b in pipe 7. The secondary air governor is therefore a variable volume governor as distinguished from the constant volume governor in the primary air pipe.

When the desired temperatures are reached in the generator and carburetor and it is desired to stop blowing and to make gas, the valves 5 and 8 in the primary and secondary air pipes are closed and at the same time a quick acting valve 33 is closed which shuts off nearly all the steam to the turbine, letting only enough pass to keep the machine running. The lever 34 to which the valve 33 is connected also operates to close a butterfly valve 35 in the inlet of the air compressor. The stoppage of the air supply permits the constant volume governor in the primary air pipe 4 to pull the throttle valve 19 in the steam main 20 wide open. A relief valve 36 in the primary air pipe relieves the same of any excess pressure due to any cause.

During the gas making period steam from any suitable source is admitted under the grate 2 by way of conduit 4^a, the supply being controlled by valve 4^b. The means for admitting oil to the carburetor is not shown but as the method followed during the gas making period is well known and forms no part of the present invention, such illustration and further description is unnecessary.

When the gas making period has ended, and it is desired to blow in again, the necessary adjustments of valves to stop the production of gas will be made; the valves 5 and 8 in the primary and secondary air pipes will be opened; the weight 27 on the secondary air governor will be reset so that it can begin its downward and outward sliding movement, and the quick-operating valve 33 and the butterfly valve 35 will be opened. A full head of steam is thus admitted to the turbine, which will accelerate very rapidly and start the air supply. The primary air governor will respond quickly and throttle down the steam to the amount required to deliver the predetermined volume.

The blowing period and the gas making period cover quite definite intervals of time, usually from six to eight minutes, and the manipulation of the valves, etc. to change from one period to the other and back again may be performed either manually by the operator or through suitable automatic devices as desired. With this arrangement, the steam consumption is kept down to that which is actually necessary to furnish the required volume of blowing air; while during the gas making period, the steam is

practically shut off, the small amount consumed in running the compressor or blower idle being negligible.

Referring now to Fig. 2, the supply of primary and secondary air is shown as being taken from a conduit or trunk line 40 which conveys air at low pressure from an air compressor or other suitable source of supply. This trunk line may supply air for one or more than one gas machine or unit. The supply of primary air passes to the generator 41 by conduit 42 corresponding to the conduit 4 of Fig. 1, while the supply of secondary air is fed to the conduit 43, by conduit 44 corresponding respectively to conduits 6 and 7 of Fig. 1.

In this form of my invention instead of regulating the supply of motive fluid to the compressor to obtain constant volume of the primary air I take my supply from a suitable source by way of conduit 40, the pressure of which is constant or otherwise, and control the volume taken therefrom by a suitable valve which in turn is controlled by a constant volume regulator arranged in the conduit 42. To this end I provide the pipe 42 with a section 45 preferably of inverted frusto-conical shape, in which is a disk float 46 of less diameter than said section. The disk is adjustably mounted on a stem 47 as by a threaded hub 48 and may be locked in any position by lock nut 49. The lower end of the stem is guided by the member 50, while its upper end is preferably offset and pivoted in one of several holes in an ear 51 carried by the valve 52 located in the pipe beyond the frusto-conical section which section is joined to the pipe by the converging section 45a. This valve is shown as being of the butterfly type and controls the flow through the conduit 42. By shifting the connection of the stem to the ear from one hole to another the valve can be adjusted to open more or less for a given movement of the float. The spindle of the valve passes through the wall of the conduit and has an arm 53 secured to it, on which is an adjustable weight 54. As will be clear, this weight tends to open the valve in opposition to the action of the float 46 which tends to close it, and hence by properly adjusting the weight 54 on the arm 53 the volume of flow through the conduit may be maintained at any desired value.

The variable volume governor shown in Fig. 2 is essentially the same as that shown in Fig. 1 and the same reference numerals have accordingly been applied thereto. Further description thereof is believed to be unnecessary.

From the explanation given of the operation in connection with the description of Fig. 1, the operation of the arrangement of Fig. 2 will be obvious, the constant volume governor in conduit 42 functioning to sup-

ply the desired volume to the generator, while the variable volume governor in conduit 44 functions to supply the gradually increasing volume desired to complete the combustion in the carburetor and super- 70 heater.

In accordance with the provisions of the patent statutes, I have described the principle of operation of my invention, together with the apparatus which I now consider to 75 represent the best embodiment thereof; but I desire to have it understood that the apparatus shown is only illustrative, and that the invention can be carried out by other means.

What I claim as new and desire to secure by Letters Patent of the United States, is:

1. In an automatic governing mechanism, a source of supply, a plurality of conduits conveying fluid therefrom, a constant volume 85 governor in one of said conduits and a variable volume governor in another of said conduits.

2. In an automatic governing mechanism, a source of supply, a plurality of conduits 90 conveying fluid therefrom, automatic means for maintaining a flow of constant volume through some of said conduits, and automatic means for maintaining a flow of variable volume through other of said conduits. 95

3. The combination with the primary and secondary air pipes of a water gas plant, of automatic means for maintaining a flow of constant volume through the primary pipe and a flow of variable volume through the 100 secondary pipe.

4. The combination in a water gas plant, of primary and secondary air pipes, a variable volume governor in the secondary air pipe, an air compressor supplying air to 105 both pipes, means for driving the compressor, and means for controlling the compressor whereby the same delivers constant volume through the primary air pipe.

5. The combination in a water gas plant, 110 of primary and secondary air pipes, a turbine driven air compressor for supplying air, a volume governor for each of said air pipes, a main supplying steam to the turbine, and a throttle valve for the turbine 115 controlled by the primary air governor.

6. The combination in a water gas plant, of primary and secondary air pipes, a turbine driven air compressor for supplying air, a volume governor for each of said air pipes, a main supplying steam to the turbine, a throttle valve in said main, connections between said valve and the primary air governor, and means for varying the action of the governor on the throttle valve 120 to insure the delivery of any desired constant volume of primary air.

7. A volume governor for flowing fluids, comprising a conduit, a valve controlling the passage of fluid therethrough, a float in 130

the conduit located in advance of the valve as regards the direction of flow, connections between said float and valve, and means for automatically increasing the resistances of said valve to the closing action of the flowing fluid upon the float.

8. A volume governor for flowing fluids, comprising a conduit, a valve controlling the passage of fluid therethrough, a float in the conduit located in advance of the valve as regards the direction of flow, connections between the float and valve, means biasing said valve to an open position in opposition to the action of the flowing fluid on the float, and means for automatically increasing the action of the biasing means.

9. A volume governor for fluids, comprising a conduit having an enlarged section and a section converging to a smaller diameter, a disk float in said enlarged section, a butterfly valve in the smaller section, connections between said valve and float, and means for automatically increasing the resistance of said valve to the closing action of the flowing fluid upon said float.

10. A volume governor for fluids, comprising a conduit having a frusto-conical section and a section converging to a smaller diameter, a disk float in said frusto-conical section, a butterfly valve in the smaller section, connections between said valve and

float, a weight counterbalancing the effect of the flowing fluid tending to close said valve, and means for automatically increasing the action of said weight.

35

11. The combination in a water gas plant, of primary and secondary air pipes, a disk float in each pipe, a valve in the secondary pipe, a connection between the valve and float, means for automatically increasing the resistance of said valve to the closing action of the flowing fluid upon said float, and means controlled by the float in the primary pipe for maintaining a flow of constant volume through such pipe.

40

12. The combination in a water gas plant, of primary and secondary air pipes, a disk float in each pipe, a valve in the secondary pipe, a connection between the valve and float, means for automatically and progressively increasing the resistance of said valve to the closing action of the flowing fluid upon said float, and means controlled by the float in the primary pipe for maintaining a flow of constant volume through such pipe.

50

In witness whereof, I have hereunto set my hand this sixth day of February, 1914.
